UNITED STATES PATENT OFFICE

FREDERICK THOMAS PEAK, OF NEW YORK, N. Y.

TELEPHONE ATTACHMENT

Application filed March 26, 1929. Serial No. 350,083.

This invention relates to telephone attachments.

It is among the objects of the present invention to provide an attachment for telephones which may be utilized to cut off sound waves to the diaphragm of the transmitter.

It is a further object of the invention to provide a telephone attachment which includes a shutter for cutting out sound waves to the transmitter and electrical means for actuating the shutter.

It is a still further object of the invention to provide a telephone having an electrical control transmitter shutter and a circuit controller for operating said shutter mounted upon the receiver in such manner as to provide for the operation of the shutter by the receiver holding hand.

The present invention is designed to provide means for closing the transmitter during the period when the party using the device listens to the person speaking at the other end of the line, when the telephone is being used in noisy surroundings. In many instances, in operating a telephone, it is necessary to hold the hand or the cheek against the transmitter to prevent noises being picked up thereby and carried to the receiver. In this connection, it will be understood that local noises entering the mouthpiece of the transmitter of a telephone pass directly through the instrument to the receiver where they are clearly audible oftentimes rendering the speech from the opposite end of the system inaudible.

Other important objects of the present invention include the combination and interrelation of parts, whereby the whole forms a simple and efficient structure readily designed to meet the demands of economic manufacture.

Numerous other objects and features of the present invention will be apparent from a consideration of the specific specification taken in conjunction with the accompanying drawings, in which

Figure 1 is a perspective view of one form of my present invention applied to the conventional type of desk telephone now in use;

Fig. 2 is a front elevation of the shutter and shutter control structure;

Fig. 3 is a sectional view taken through the lines 3—3 of Fig. 2;

Fig. 4 is a top plan view of that portion 55 of the device shown in Figs. 2 and 3;

Fig. 5 is a bottom plan view of the device shown in Figs. 2 and 3;

Fig. 6 is a sectional view showing the circuit controller applied to the telephone receiver;

Fig. 7 is a sectional view taken on the lines 7—7 of Fig. 6;

Fig. 8 is a detail view of part of the circuit controlling assembly, and

Fig. 9 is a wiring diagram for the apparatus.

Referring more particularly to Figs. 1 to 5 inclusive of the drawings, it will be seen that the invention includes a shutter housing 70 comprising a back 10 and casing 11. The housing is adapted to be secured to the transmitter by the threaded engagement of an extending sleeve 12 with the mouthpiece receiving portion of the transmitter. The usual mouthpiece 13 is threadedly engaged through the casing 11, in alignment with the sleeve 12, the engagement being with an internally threaded bushing 14 which is secured to the casing 11. For controlling the admittance of sound waves through the sleeve 12 to the transmitter, a shutter 15 is provided, which includes a plurality of slots 16, which co-operate with slots 17 in the inner end of the sleeve 12. It will be understood 75 that registration of the slots 17 and 16 permit free passage of sound waves therethrough and that movement of the shutter 15 to break the registration of the slots will prevent the passage of sound waves therethrough. It will further be seen that the inner ends of the sleeve 12 and bushing 14 co-operate with guiding members 18, to provide for the reciprocation of the shutter 15 therebetween. The shutter 15 is adapted for 80 actuation in response to the movement of an associated shaft 19 secured between bifurcations 20 depending from the shutter. For manually controlling the shutter, should the shaft 19 fail to properly operate, the shutter 85

actuation in response to the movement of an associated shaft 19 secured between bifurcations 20 depending from the shutter. For manually controlling the shutter, should the shaft 19 fail to properly operate, the shutter 100

15 is provided with an extending member 21 which when the shutter is in fully raised position cutting off the flow of sound waves and as indicated in Fig. 3, extends through 5 the casing 11 and may be manually depressed to restore the shutter to registering position.

For normally raising the shutter in the raised closing position shown in Fig. 3, the shaft 19 is associated with a bar 22 through 10 which the shaft 19 is secured by the provision of a locking nut 23. The bar or arm 22 is mounted on its extremities for free movement over a pair of vertical guide members 24, which are surrounded by expansion 15 springs 25, which abut the under face of the arm 22, thus normally urging it upwardly. The lower ends of the springs 25 abut an angled bracket 26, to which the guides 24 are secured and which is secured to the back 10 20 by suitable threaded members 27.

For moving the shaft 19 downwardly against the tension of the springs 25, thus aligning the slots 16 and 17 to permit the passage of sound waves to the transmitter, a 25 pair of electromagnets 28 are provided, the poles 29 of which utilize the arm 22 as an armature, whereby energization of the magnets moves the arm 22 downwardly thus moving the shaft 19 to affect the shutter 15. The 30 electromagnets 28 are mounted upon a base 30, which acts to close the lower end of the magnetic field therebetween. The base 30 is mounted upon the bracket 26 and is centrally apertured to receive therethrough the 35 lower end of the shaft 19 which is preferably journaled through the bracket 26. For retaining the shutter 15 in its downward position against the tension of the springs 25 as brought about by the influence of the magnets 28, the shaft 19 is provided with a projecting portion 31, which is adapted to be engaged by the inwardly extending portion 32 of the pivoted arm 33. The arm 33 is pivoted as at 34, to depending apertured bifurcations 35 of the bracket 26. The arm 33 is normally urged toward the center of the shaft 19 by the provision of a simple leaf spring 36, mounted upon the casing 11. It will readily be seen that as the shaft 19 is 50 moved downwardly, the portion 32 of the arm 33 will move inwardly to engage the upper face of the projecting portion 31 of the shaft, thus retaining the shaft in its downward position against the tension of the 55 springs 25.

For releasing the shaft 19, the lower end of the arm 33 is associated with an electromagnet 37, the outer end of the pole 38 of which is arranged upon energization of the 60 magnet to move inwardly the outer end 39 of the arm 33, pivoting the same about its pivot 34 and against the tension of the spring 36, whereby the extremity 32 will move outwardly from the shaft 19, thus releasing the 65 projecting portion 31 thereof. From the

drawings it will be seen that the electromagnet 37 is mounted in conjunction with the bracket 26 and the base 10 by the provision of a suitable threaded engaging means 40.

For controlling the energization of the 70 magnets 28 and 37, a circuit controller, Fig. 6, is associated with the receiver 41. The structure herein presented includes a pair of interthreadedly engaging members 42 and 43, which jointly engage over the rim 44 of the receiver and thus retain themselves in proper position. Associated between the lower ends of the member 42, there engages a semi-circular conductor shield 45 shown in Fig. 8. The shield includes projections 46 80 which are received in suitable apertures 47 formed in the member 42. By referring to Fig. 6, it will be seen that the shield 45 extends up the receiver to provide for the guiding of a conductor, as will be hereinafter 85 described.

Associated with the inner member 42, a circuit controller is provided, which includes a pivoted conducting member 48, which upon downward movement is adapted to engage a 90 contact point 49 for completing the electrical circuit therebetween, and which upon upward movement is adapted to contact with a contact 50 to complete the electrical circuit therebetween. The conducting member 48 is 95 urged by association with the spring member 51 to normally engage with the upper contact 50. By referring to Fig. 6, it will be seen that contacts 49 and 50 and the conducting member 48 are mounted within a suitable 100 protecting housing 52 carried by the member 42.

By referring more particularly to the diagrammatical illustration of the circuit as shown in Fig. 9, the actuation of the magnet for controlling the shutter will be more fully 105 understood. A source of electrical energy, such as a battery, is provided as at 53, one pole of which leads to the binding post 54 mounted upon the bracket 26, from which extends a conductor 55, which is joined with the 110 under arm 56 of a circuit maker-and-breaker, which also includes the upper arm 57. By referring to Fig. 2, it will be seen that the arm 57 is adapted for movement in response to movement of the arm 22. Thus the circuit 115 between the arms 57 and 56 is automatically broken when the shutter is in upward closed position, and the circuit is automatically completed therethrough when the shutter moves downwardly. The arm 57 is associated with 120 a conductor 58 which leads to the electromagnet 37 from which a conductor 59 extends to the central binding post 60 associated with which is a conductor 61 leading to the lower contact 49 of the circuit controller on the receiver. 125

One side of the electromagnets 28 is also joined with the conductor 55 and receives energy therethrough, while the other side of the magnets is connected with a conductor 62 to 130

5 a circuit controller including a moving arm 63 and a stationary arm 64. The arm 63 is associated for movement in response to outward movement of the end 39 of the arm 33, which outward movement breaks the contact between the arms 63 and 64. When the end 10 39 of the arm 33 is drawn inwardly under the influence of the magnet 37, the arms 63 and 64 contact. The arm 64 is associated with a conductor 65 which leads to a binding post 66 mounted upon the bracket 26 from which extends a conductor 67 which leads to the upper contact 50 of the circuit controller on the receiver. The conducting arm 48 is 15 associated by a conductor 68 to the opposite side of the battery 53.

In the operation of the device the normal position of the shutter is in the lowered opened position whereby it is extended ready for use. The conductor 48 is by means of the 20 spring member 51 also in raised position completing the circuit between the conductors 68 and 67. With the shutter in lowered opened position and the conductor 48 in raised position, the contact members 63 and 64 are open and the circuit which is completed between the conductors 68 and 67 is broken between these contacts. When the arm 48 is moved down, the circuit is completed between the conductors 68 and 61 thus permitting the 25 flow of current through the magnet 37, the contact members 56 and 57, and through the conductor 55 to the battery. This energization of the magnet 37 releases the arm 33, whereby the springs 25 urge the arm 22 upwardly, thus closing the shutter, which action separates the contacts 56 and 57, whereby only an instantaneous flow of current is permitted. When the arm 48 is again released 30 to move upwardly, the circuit is then completed through the conductors 68 and 67. The inward movement of the arm 33 moves the contact 63 for connection with the contact 64. Thus the current is supplied through the conductors 65 and 62 to energize the magnets 28 and to be completed through the conductor 55 to the battery, whereby the arm 22 will be restored to its open position, the arm 33 moving outwardly to break the contact between the points 63 and 64, and thus utilizes only 35 an instantaneous flow of the current.

From the foregoing it will be seen that the energy utilized by the device is small, in that the energization of the magnets is only instantaneous; as soon as their work is completed, the circuit is automatically cut off.

It will readily be seen that the invention is simple in construction and operation and that numerous changes and modifications and the full use of equivalents may be resorted to without departing from the spirit or scope of the invention as outlined in the appended claims.

What is claimed is:

65 1. A telephone apparatus, including a

shutter for the transmitter, and electromagnetic means for controlling said shutter, said means including a shaft associated with said shutter, a cross arm mounted upon said shaft and electromagnets operable upon energization to move said cross arm. 70

2. A telephone apparatus, including a shutter for the transmitter, and electromagnetic means for controlling said shutter, said means including a shaft associated with said shutter, a cross arm mounted upon said shaft, electromagnets operable upon energization to move said cross arm, and resilient means associated with said cross arm for normally urging the same in shutter-closing position 80

3. A telephone apparatus, including a shutter for the transmitter, and electromagnetic means for controlling said shutter, said means including a shaft associated with said shutter, a cross arm mounted upon said shaft, electromagnets operable upon energization to move said cross arm, resilient means associated with said cross arm for normally urging the same in shutter-closing position, and means for holding said shutter in opened 90

4. A telephone apparatus, including a shutter for the transmitter, and electromagnetic means for controlling said shutter, said means including a shaft associated with said shutter, a cross arm mounted upon said shaft, electromagnets operable upon energization to move said cross arm, resilient means associated with said cross arm for normally urging the same in shutter-closing position, means for holding said shutter in opened position, and electromagnetic means for releasing said holding means. 95

5. A telephone apparatus, including a shutter for the transmitter, electromagnetic means for controlling said shutter, a circuit controller means for said electromagnetic means, said circuit controller being mounted on the telephone receiver, a circuit including said circuit controller and said electromagnetic means, and means in said circuit for automatically disconnecting said circuit when said electromagnetic means has functioned. 105

6. In a device of the character described, a normally closed shutter, electromagnetic means for opening said shutter, electromagnetically operated means for retaining said shutter in closed position, a remotely positioned circuit controller for controlling said electromagnets, and means controlled by the position of said shutter to effect the control of the circuit in response to said circuit controller, said means including a plurality of circuit controllers. 115

7. In a device of the character described, a normally closed shutter, electromagnetic means for opening said shutter, electromagnetically operated means for retaining said shutter in closed position, a remotely posi- 120

125

130

tioned circuit controller for controlling said electromagnets, and means controlled by the position of said shutter to effect the control of the circuit in response to said circuit controller, said means including a plurality of circuit controllers, one of said controllers being associated with the electromagnetic shutter-opening means.

8. In a device of the character described, 10 a normally closed shutter, electromagnetic means for opening said shutter, electromagnetically operated means for retaining said shutter in closed position, a remotely positioned circuit controller for controlling said 15 electromagnets, and means controlled by the position of said shutter to effect the control of the circuit in response to said circuit controller, said means including a plurality of circuit controllers, one of said controllers 20 being associated with the electromagnetic shutter-opening means, and one of said circuit controllers being associated with the electromagnetic releasing means.

9. The combination of a telephone apparatus having a transmitter and a receiver with a shutter associated with said transmitter, means for normally holding said shutter in one position, electromagnetic means for causing the shutter to take another position and preventing noises in the environment surrounding the telephone from being transmitted through the telephone, and manual means for closing an electrical circuit to energize said electromagnetic means.

35 10. The combination of a telephone apparatus having a transmitter and a receiver with a shutter associated with said transmitter, means for normally holding said shutter in one position, electromagnetic means for closing said shutter on said transmitter and preventing noises in the environment surrounding the telephone from being transmitted through the telephone, an electrical circuit connected to said electromagnetic means and 40 a switch interposed in said circuit whereby the electromagnetic means can be energized and actuated to close the shutter when the telephone user desires to prevent noises from the environments surrounding the telephone 45 50 from being transmitted therethrough.

11. The combination of a telephone apparatus having a transmitter and a receiver with a shutter associated with said transmitter, means for normally holding said shutter in one position, electromagnetic means for closing said shutter on said transmitter and preventing noises in the environment surrounding the telephone from being transmitted through the telephone, an electrical 55 60 circuit connected to said electromagnetic means and a switch mounted upon the receiver and interposed in said circuit, whereby the electromagnetic means can be energized and actuated to close the shutter when 65 the telephone user desires to prevent noises

from the environments surrounding the telephone from being transmitted therethrough.

12. The combination of a telephone apparatus having a transmitter and a receiver with a shutter associated with said transmitter, said shutter being normally in an opened position, electromagnetic means associated with said shutter for closing the latter and an electrical circuit connected to said electromagnetic means, a battery connected in said electrical circuit, a switch for closing said electrical circuit and energizing said electromagnetic means to cause the closing of the shutter, electromagnetically operated means for holding said shutter in a closed condition and means associated with said shutter and controlled by the position of the latter to effect a control of the electrical circuit in response to the action of the aforesaid switch.

13. The combination of a telephone apparatus having a transmitter and a receiver with a normally open shutter for the transmitter, a stop for holding said shutter in an open position, an electromagnet for withdrawing said stop and permitting the closing of said shutter, an electrical circuit connected to said electromagnetic means including a two-way switch and a battery, resilient means for causing the shutter to close when the said electromagnet is energized by closing said switch and said stop is withdrawn, a circuit breaker operatively associated with said shutter in such a manner that when the shutter reaches its closed position the electrical energy flowing through said circuit from the battery is discontinued, a second electromagnet associated with the shutter for moving the shutter into an open position against the action of the aforesaid resilient means, a circuit control means connected with a circuit leading to said second electromagnet and adapted to control said latter circuit in accordance with the position of the armature of said first electromagnet, said latter circuit being open when the armature of said first electromagnet is in an extended position and closed when the said armature is in a retracted position and the two-way switch is in a released condition.
